United States Patent Office.

ANDREW MATSON, OF ELIZABETH, NEW JERSEY.

Letters Patent No. 91,033, dated June 8, 1869.

IMPROVED IRONING-BOARD.

The Schedule referred to in these Letters Patent and making part of the same.

To all whom it may concern:

Be it known that I, ANDREW MATSON, of Elizabeth, in the county of Union, and State of New Jersey, have invented a new and improved Ironing-Board; and I do hereby declare that the following is a full, clear, and exact description thereof, which will enable others skilled in the art to make and use the same, reference being had to the accompanying drawings, forming part of this specification, in which—

Figure 1 is a side view of my improved ironing-board.

Figure 2 is an end view of the same.

Figure 3 is a detail top view of the pivoted table or frame.

Similar letters of reference indicate corresponding parts.

My invention has for its object to furnish a simple and convenient ironing-board, which shall be so constructed and arranged, that when not in use, it may be folded up so as to occupy but little more space than an ordinary ironing-board.

And it consists in the construction and combination of the various parts, as hereinafter more fully described.

A is the board upon which the ironing is done, and which is made in about the form and size of an ordinary ironing-board.

One end of the board **A** is designed to rest upon a table or other suitable support, and has a cleat, **a'**, attached to its lower side to keep it from sliding forward upon said table.

To the under side of the board **A**, near its other end, are attached two wooden ears or brackets **B**, to which is pivoted the upper end of the frame **C**, as shown in figs. 1 and 2.

The frame **C** is strengthened and held in its proper relative position by the brace-arm **D**, the lower end of which is pivoted to the frame **C**, and the upper end

of which is detachably secured to an eye or other catch attached to the end of the board **A**, by a spring, hook, or other easily-detachable means.

By this means the outer end of the board is securely supported while being used.

To the inner side of the lower part of frame **C** is pivoted a frame or table, **E**, the forward or inner end of which is supported by short legs **F**, which, when not required for use, may be turned down, so as to lie along the side edges of the table **E**, so as to be entirely out of the way.

By this construction the ironing-board, when not in use, by simply detaching the upper end of the brace-arm **D**, may be folded together so as to require but little more room for storage than a simple board.

In ironing ladies' skirts and other similar articles, the forward end of the board may be raised, and the garment be passed over the board, allowing it to be conveniently ironed.

If the skirt be full, the lower parts will rest upon the table **E**, and will thus be kept from becoming soiled by coming in contact with the floor.

Having thus described my invention,

What I claim as new, and desire to secure by Letters Patent, is—

An improved ironing-board, formed by the combination of the board **A**, pivoted supporting-frame **C**, pivoted brace-bar or arm **D**, and pivoted table or platform **E**, provided with the pivoted legs **F**, with each other; said parts being constructed and arranged substantially as herein shown and described, and for the purpose set forth.

The above specification of my invention signed by me, this 26th day of April, 1869.

A. MATSON.
